His Attorney.

UNITED STATES PATENT OFFICE.

WILLIAM C. WHITE, OF SCHENECTADY, NEW YORK, ASSIGNOR TO GENERAL ELECTRIC COMPANY, A CORPORATION OF NEW YORK.

WIRELESS SIGNALING SYSTEM.

1,310,041.

Specification of Letters Patent. Patented July 15, 1919.

Application filed January 18, 1917. Serial No. 143,045.

To all whom it may concern:

Be it known that I, WILLIAM C. WHITE, a citizen of the United States, residing at Schenectady, in the county of Schenectady, State of New York, have invented certain new and useful Improvements in Wireless Signaling Systems, of which the following is a specification.

My present invention relates to the production of radio frequency continuous electrical oscillations and to the control of such oscillations for the purpose of transmitting wireless signals.

It has been found that an electron discharge device comprising an incandescent cathode, a coöperating anode and a discharge controlling member or grid inclosed in an evacuated envelop may be employed for producing radio frequency oscillations.

In order to secure this result a source of energy is placed in the plate circuit of the device which includes the cathode and anode and an inductance, and this circuit is coupled with the grid circuit which includes the cathode and grid and a second inductance. If a suitable degree of coupling is provided between the two circuits enough energy is transferred from the plate circuit to the grid circuit to impress upon the grid the potential necessary to control the flow of current in the plate circuit in the desired manner.

In some cases the electrostatic coupling between the two circuits which is always present by reason of the capacity between the electrodes is sufficient to bring about the desired result. In other cases this coupling is supplemented in various ways, as for example, by a coupling between the inductances in the two circuits, or by an additional electrostatic coupling consisting of a condenser between the grid and anode or by a combination of the two forms of coupling. Because of the unidirectional conductivity of the electron discharge de-

vice the current in the plate circuit will usually be pulsating in character. For practical purposes, however, it may be considered as being made up of two components, one a constant direct current and the second an alternating current superimposed upon the direct current. In order to utilize this alternating component in an antenna it has been customary to couple a coil in the antenna with the plate circuit inductance.

It has, however, been suggested that the

system might be simplified by including the plate circuit inductance directly in the antenna circuit and thus impressing the alternating component of the plate current upon the antenna, thereby avoiding the necessity of an inductive coupling between plate circuit and antenna, and the use of a separate coil with the unavoidable losses therein. In the practical application of this arrangement, however, it has been found that the source of potential used for heating the cathode, together with the auxiliary apparatus used for controlling the heating current, instead of being at a fixed low potential with respect to earth, as is usual in the prior arrangement, is at a potential which alternately varies at the frequency generated between positive and negative values with respect to earth, and that this potential may rise to such a high value that it becomes inconvenient to insulate from earth the source which furnishes the heating current.

One of the objects of my invention is to provide a connection whereby this disadvantage may be avoided and the advantage of the direct connection of plate inductance to the antenna may be retained.

In order to attain this object I divide the plate circuit inductance into two parts and arrange the two parts in such a way that they furnish two parallel paths for the high frequency component of the plate current. One of these inductances is included directly in the antenna circuit and the second inductance is so closely coupled to the first that for all practical purposes it may be considered as being directly in the antenna circuit. The source of current for heating the cathode is connected to the ends of those inductances which are always at a low potential with respect to earth in such a way that the heating current flows through the two inductances in series. As a result the source which furnishes the heating current and the auxiliary regulating apparatus will always be at a low potential with respect to earth.

In order to utilize the continuous radio frequency oscillations, produced by the arrangement described, for signaling purposes, it is sometimes desirable that they be broken up into groups of an audible frequency.

A further object of my invention is to

provide a simple and effective means for automatically breaking up the oscillations in this way when it is desired to transmit telegraphic signals.

5 In accomplishing this result I provide means for short circuiting one of the inductances employed, at regular intervals, and thereby interrupting the production of oscillations. With this arrangement the device 10 normally impresses radio frequency oscillations upon the antenna and when signals are sent the oscillations are broken up into groups of an audible frequency. The same effect may also be secured by arranging the 15 apparatus in such a way that one of the circuits is normally open and hence no oscillations are produced. By alternately closing and opening the circuit at regular intervals groups of oscillations may be produced at an 20 audible frequency.

25 My invention will best be understood by reference to the following description taken in connection with the accompanying drawing in which Figure 1 shows diagrammatically one embodiment of my invention, and Fig. 2 shows a modification thereof.

As indicated in the drawing, an electron 30 discharge device is used which comprises an electron emitting cathode 1 of filamentary form, a plate shaped anode 2, and a grid 3 interposed between cathode and anode, all inclosed in an evacuated envelop 4. The plate circuit of this device includes the two parallel inductances 5 and 6 and a source 35 of energy 7 which may be a direct current generator as indicated, or any other convenient source of direct current. The current for heating the cathode 1 to cause it to emit electrons is also derived from the 40 source 7, the resistance 8 being included in series with the cathode and the inductances 5 and 6 in order to reduce the voltage which will be applied to the terminals of the cathode. The value of the heating current 45 is regulated in the usual manner by varying the resistance in the circuit by means of the variable connection 9. A condenser 10 which is in series with inductance 6 in the plate circuit serves as a low resistance path for the 50 alternating component of the current flowing through the inductance 6, and as an open circuit to the direct current used for heating the cathode. The grid circuit comprises an inductance 11 and may also include a battery 55 12 for the purpose of giving the grid a normal potential at which the device operates most efficiently. The antenna 13 is connected to a suitable point, such, for example, as the point 14 in the inductance 11, and 60 variations in the tuning of the system and in the potential impressed upon the antenna may be brought about by varying the point of connection of the antenna. The antenna is grounded through inductance 5 and a condenser 15. The object of this condenser is

to avoid connecting the source 7 direct to earth. If there is no objection to such a connection the condenser 15 may be omitted. With the connection described the grid and plate circuits are coupled electrostatically 70 by reason of the capacity between the electrodes 1, 2 and 3, and this coupling is supplemented by the capacity of the antenna which is, in effect, connected between the grid 3 and anode 2. The coils, 5, 6 and 11 may also be arranged to furnish any desired degree of inductive coupling between the two circuits.

The arrangement thus far described is adapted to produce radio frequency continuous oscillations, the frequency of which will be determined by the natural period of the antenna system. In order to interrupt these oscillations at regular intervals when it is desired to send signals, I provide an auxiliary circuit including a key 16 which is normally open and a buzzer consisting of a coil 17 controlling an armature 18, which makes a contact at 19 when the coil 17 is not energized. A small portion of the potential across resistance 8 is utilized for operating the buzzer, the potential used being regulated by the sliding contact 20. As long as the key 16 is open this auxiliary circuit is open and oscillations will be produced. When the key 16 is closed however the inductance 6 is short circuited and the oscillations will immediately stop. The coil 17 will then be energized and contact broken at 19, the auxiliary circuit thus being opened allowing the oscillations to start again. At the same time coil 17 will be deenergized and contact 19 will again close and the oscillations be interrupted. This action will continue as long as the key 16 is closed and by proper adjustment of the buzzer the interruptions may be made to occur at any frequency desired. As a result continuous oscillations will be produced in the antenna in groups as long as the key 110 16 is depressed and these groups may be produced at any audible frequency desired by varying the adjustment of the buzzer. The length of each group of oscillations and the length of the period between groups may 115 also be varied by varying the adjustment of the buzzer.

The arrangement shown in Fig. 2 differs from that shown in Fig. 1 merely in the arrangement of the auxiliary circuit for controlling the oscillations. In this case the grid circuit is so arranged that the device is normally inoperative for producing oscillations. When the key 16 is depressed the grid circuit is closed through the key and 120 contact 19 and oscillations are produced. At the same time the coil 17 is energized and the contact broken at 19 and oscillations are thereby interrupted. A portion of the battery 12 in the grid circuit may be utilized 125

for operating the buzzer, variable connections 21 being employed for securing the desired operating voltage. The iron core inductance 22 in the buzzer circuit offers a 5 high impedance to the high frequency current and thus prevents the production of oscillations when the key 16 is open.

It will of course be apparent that many modifications in the specific arrangement of 10 the oscillation controlling means may be made without departing from the scope of my invention. Instead of short circuiting the inductance in either the grid or plate circuit in the general manner indicated in 15 Fig. 1 to stop oscillations the connections may be made in such a way as to open one of the circuits to accomplish the same result by an arrangement of the general type shown in Fig. 2.

20 What I claim as new and desire to secure by Letters Patent of the United States, is:—

1. The combination in a wireless signaling system of an antenna, an electron discharge device connected to said antenna and having 25 plate and grid circuits so adjusted and coupled to each other that radio frequency continuous oscillations will be produced in said antenna, an inductance in said plate circuit, and means operatively related to said 30 plate circuit for intermittently short-circuiting said inductance and thereby interrupting the production of oscillations by said electron discharge device.

2. The combination in a wireless signaling system of an antenna, an electron discharge device connected to said antenna and having 35 plate and grid circuits so adjusted and coupled to each other that radio frequency continuous oscillations will be produced in said antenna and means operatively related to the plate circuit for intermittently short circuiting a portion thereof and thereby interrupting the production of oscillations.

3. The combination in a wireless signaling 45 system of an antenna, an electron discharge device connected to said antenna and having plate and grid circuits containing inductances and so adjusted and coupled to each other that radio frequency continuous oscillations will be produced in said antenna, and means for intermittently short circuiting one 50 of said inductances and thereby interrupting the production of oscillations at an audible frequency.

4. The combination in a system for producing alternating currents of an electron discharge device comprising a cathode adapted to be heated to incandescence, a co-operating anode and a grid inclosed in an evacuated envelop, two inductances connected in the plate circuit of said device in such a way that alternating current produced in the circuit will flow through the two in parallel, and that the current necessary for heating the cathode to incandescence 65 will flow through the two in series, and a grid circuit containing an inductance and coupled to the plate circuit in such a manner that radio frequency currents will be produced in the plate circuit.

5. The combination in a wireless signaling system of an antenna, an electron discharge device connected to said antenna and having plate and grid circuits containing inductances and so adjusted and coupled to each 70 other that radio frequency continuous currents will be produced in said antenna, the inductance in the plate circuit comprising two coils inductively related to each other and so connected that the radio frequency currents 75 flow through the two in parallel, and means for intermittently short-circuiting one of said coils and thereby interrupting the production of oscillations at an audible frequency.

6. The combination in a wireless signaling system of an antenna, an electron discharge device connected to said antenna and comprising a cathode adapted to be heated to incandescence, a co-operating anode and 90 a grid inclosed in an evacuated envelop, two inductances connected in the plate circuit of said device in such a way that alternating currents produced in the plate circuit will flow through the two in parallel, 95 and that the current necessary for heating the cathode to incandescence will flow through the two in series, a grid circuit containing inductance and coupled to the plate circuit in such a way that radio frequency 100 continuous oscillations will be produced in the antenna and means for intermittently short circuiting one of the inductances of the system and thereby interrupting the production of oscillations at an audible frequency.

In witness whereof, I have hereunto set my hand this 17th day of January, 1917.

WILLIAM C. WHITE.
